SASH AND STORE FRONT CONSTRUCTION

Clyde D. Lowry, Toledo, Ohio, assignor to Libbey-Owens-Ford Glass Company, Toledo, Ohio, a corporation of Ohio

Application November 17, 1938, Serial No. 240,927

4 Claims. (Cl. 20—56.4)

The present invention relates to metal sash and store front constructions and has for its primary object the provision of novel and improved means for mounting and retaining a pane of glass in proper adjusted position.

Another object of the invention is the provision of a sash or store front construction embodying inner and outer glass retaining sections of improved construction and arrangement associated with one another in a novel manner and having novel means for connecting the said sections together to firmly clamp the pane of glass in position therebetween.

Another object of the invention is the provision of a sash or store front construction of maximum simplicity, ease of assembly and operation, and embodying clip members or the like associated with the outer section and actuated by adjusting means associated with the inner section to effect the securing of the pane of glass in place.

A further object of the invention is the provision of improved tensioning means embodying a plurality of cooperating clip members and adjusting members, together with positive means for preventing further tightening of said adjusting members when said clip members have caused the sash sections to exert a substantially predetermined clamping pressure upon the glass.

A still further object of the invention is the provision of improved tensioning means for connecting the stationary and movable sash sections together in such a manner that they will exert a resilient cushioned pressure upon the pane of glass while at the same time permitting relative movement between the said sections to take care of vibrations and expansion and contraction of the glass and metal sash construction without disturbing the setting of the glass or causing injury thereto.

Other objects and advantages of the invention will become more apparent during the course of the following description, when taken in connection with the accompanying drawings.

In the drawings, wherein like numerals are employed to designate like parts throughout the same:

Fig. 1 is a front elevation illustrating a store front embodying the present invention;

Fig. 2 is a vertical transverse sectional view through the metal sash construction provided by the invention; and

Fig. 3 is a similar view showing a modified form of the invention.

In Fig. 1 of the drawings, the numeral 5 designates in its entirety a glazed opening in which is mounted a sheet or pane of glass 6 supported in the window opening by the metal sash construction 7 arranged at the top, bottom and sides of said window. The front wall of the building may be faced with stone, Vitrolite, or other ornamental slabs or panels 8.

With reference particularly to Fig. 2, the metal sash construction 7 is mounted upon a wooden sill 9 in front of a wooden back stop 10 which is carried by said sill. The sash construction comprises a stationary rear section 11 and a movable front section 12 associated with one another to clamp the pane of glass 6 in position therebetween. The rear sash section 11 comprises a vertical back wall 13 which abuts the wooden back stop 10 and is secured thereto by wood screws or the like 14. Formed integral with the back wall 13, adjacent its upper end, is an inwardly directed gutter portion 15 terminating in a substantially vertical lip 16 engaging the inner face of the pane of glass 6.

The back wall 13 is provided at its lower end with a forwardly directed horizontal ledge 17 and formed integral with the outer end thereof is the arcuately shaped bottom wall or base portion 18. The bottom wall 18 has its upper surface longitudinally grooved or channeled as at 19 to form a cradle portion. Formed integral with the ledge 17, intermediate the front and rear ends thereof, is the depending web portion 20 provided with a rearwardly directed wedge portion 21 cooperating with said ledge to provide a rearwardly facing, horizontal channel 22.

The bottom wall 18 and wedge portion 21 of the rear section 11 do not contact directly with the wooden sill 9 but instead preferably rest upon a horizontal metal sill plate 23 covering the upper surface of the wooden sill and being suitably secured thereto by screws or the like. The sill plate 23 may be provided at its outer end with a downturned flange 24 overlapping the outer marginal portions of the adjacent facing panels 8 and at its opposite end with a vertical upstanding leg 25 formed at its upper end with a forwardly directed wedge portion 26 snugly received within the channel 22 in the rear sash section. The cooperating wedge portions 21 and 26 form a seal for preventing the seepage of water and moisture between the metal sash construction 50 and wooden sill and back stop, thereby maintaining the said sill and back stop perfectly dry and eliminating dry rot, deterioration, and warpage.

The front sash section 12 comprises a face 55

- piece 27 having the desired profile and being provided at its upper end with a downturned lip 28 engaging the outer face of the pane of glass 6. The face piece 27 is formed at its lower end with 5 a longitudinally extending, inturned flange 29 fitting beneath the forward upturned end 30 of the cradle portion 18 and having its inner edge 31 arcuately curved to correspond to the curved under side 32 of the said cradle portion.
- 10 The downturned glass engaging lip 28 of the front section 12 cooperates with the face piece 27 to provide a recess 33 for receiving the upper ends of a plurality of clip members 34. Each clip member comprises a substantially vertical 15 arm spring 35 bent at its upper end as at 36 and inserted within the recess 33, the end of said bent portion 36 engaging in a notch 37 in said face piece. The opposite or lower end of the spring arm 35 is similarly bent but in the opposite direction as at 38 and carries a rigid body member 39. The body member 39 is formed with a recess 40 within which the lower bent portion 38 of the spring arm is received. The body member is also rockably mounted within the 25 cradle portion 18 of the rear section 11 and is provided with an arcuately curved bottom surface 41 corresponding to and having sliding contact with the upper arcuately grooved surface 19 of said cradle portion. The contacting surfaces 19 and 41 of the cradle portion 18 and rigid body member 39 respectively are preferably struck in the arc of a circle to afford the requisite seat or bearing for the said body member upon rocking thereof.
- 30 The body member 39 is formed, forwardly of the spring arm 35, with an upstanding finger 42 and is likewise provided with a rearwardly extending substantially horizontal lever arm 43 engageable by an adjusting screw 44 which is 35 threaded through the gutter portion 15 of the rear section 11. The lever arm 43 is provided with a depending lug 45 which is adapted to engage the horizontal ledge 17 upon rocking of the body member 39 within cradle portion 18 40 and which serves as a positive stop to prevent excessive tightening of the adjusting screw 44.
- When installing a pane of glass 6 in an opening to be glazed, the metal sill plate 23 is first 45 properly positioned upon the wooden sill 9 and the rear sash section 11 is then associated therewith and secured by the screws 14 to the wooden back stop 10 and also by similar screws, if desired, to the wooden sill 9. The pane of glass 6 is then set in place and supported at its lower 50 edge upon a plurality of setting blocks 46 of any desired construction and which are arranged at spaced intervals longitudinally of the rear sash section in the customary manner. After the glass pane has been properly positioned upon the 55 setting blocks, with the rear surface thereof in contact with the lip 16 of rear section 11, the movable front section 12 is properly associated with said rear section. This is done by bringing the inner edge 31 of the flange 29 of said front 60 section into engagement with the curved under side 32 of the cradle portion 18 and the lip 28 thereof in contact with the outer face of the pane of glass.
- Prior to the positioning of the movable front 65 section 12, however, a suitable number of clip members 34 are properly associated therewith and when the said front section is associated with the rear section, as explained above, the rigid body members 39 of the clip members 34 70 will be received within the cradle portion 18 of

the rear section 11. At such time, the clip members will assume the position indicated by the full lines in Fig. 2, with the arcuately curved bottom surfaces 41 of the rigid body members 39 contacting the arcuately grooved upper surface 19 of the cradle portion 18.

The adjusting screws 44 are then tightened to engage the lever arms 43 of the clip members and downward pressure upon said lever arms will cause the rigid body members 39 to be rocked 10 in a clock-wise direction within the cradle portion 18. In other words, as the body members rest or seat upon the upper arcuately grooved surface 19 of the cradle portion, they will turn or fulcrum therein with a knuckle-like action. Upon rocking movement of the rigid body members, the upstanding fingers 42 thereof will act to flex the spring arms 35 in the manner indicated by the broken lines in Fig. 2 whereby to 15 urge the lip 28 of the movable front section into yielding engagement with the glass.

In this way, the movable front section will be maintained in firm clamping engagement with the pane of glass 6 to effectively secure the same 20 in place, while the spring arms 35 will provide for a certain amount of flexibility and resiliency to take care of vibration and expansion and contraction of the glass and metal sash construction without disturbing the setting of the pane or causing injury thereto. Likewise, the liability of 25 breakage of the glass under severe wind strain and other shocks to which it may be subjected in use will be greatly reduced.

The adjusting screws 44 are adapted to be 30 tightened until the lugs 45 on lever arms 43 engage the upper surface of the horizontal ledge 17 whereupon further tightening of the said screws will be prevented. Consequently, the lugs 45 cooperate with the ledge 17 to provide a 35 positive stop means for preventing overtightening of the adjusting screws 44 and thereby effectively prevent the application of excessive clamping pressure upon the glass which might result in the breakage thereof.

The sash construction illustrated in Fig. 3 is 40 substantially the same as that disclosed in Fig. 2, with the principal difference being in the manner in which the movable front section 47 is associated with the stationary rear section 48.

The rear stationary section 48 includes a vertical back wall 49 which abuts the wooden back stop 10 and is secured thereto by screws 50. The back wall is provided, adjacent its upper end, with a forwardly directed gutter portion 51 terminating in a substantially vertical lip 52 engaging the inner face of the pane of glass 6. Formed integral with said back wall at the lower end thereof is a forwardly directed bottom wall 53 supported upon the metal sill plate 23 covering the wooden sill 9.

The bottom wall 53 of the rear section is provided intermediate its front and rear ends with the longitudinally grooved or channeled cradle portion 54 having an arcuately curved upper surface 55. The bottom wall 53 inclines forwardly 55 and upwardly from the cradle portion 54, as shown at 56, and terminates in a substantially horizontal lip 57. Depending from the bottom wall, adjacent its outer end, is a web 58 formed at its lower end with a forwardly directed flange 59, said flange cooperating with said lip to provide an outwardly opening substantially U-shaped channel 60 for receiving the lower in-turned end 61 of the movable front section 47.

The movable front section 47 comprises a face 75

piece 62 provided at its upper end with a down-turned lip 63 engaging the outer face of the pane of glass 6. Carried by the movable front section are a plurality of clip members 64, each comprising a vertical spring arm 65 secured at its upper end to the face piece and having attached to its lower end a rigid body member 66.

The body member 66 is rockably mounted within the cradle portion 54 of the rear section 10 and is provided with an arcuately curved bottom surface 67 corresponding to and having sliding contact with the upper arcuately grooved surface 55 of said cradle portion. The body member is also provided with a rearwardly extending lever arm 68 engageable by the adjusting screw 69 threaded through the gutter portion 51 of the rear section. The lever arm 68 is provided with a depending lug 70 adapted to engage the bottom wall 53 of the rear section upon rocking 15 of the body member 66 within the cradle portion 54 to prevent over-tightening of the adjusting screw 69.

In the operation of this form of the invention, the pane of glass 6 is first properly set in place 25 with respect to the rear stationary section 43 after which the front movable section 47 is associated with the rear section. This is done by slipping the lower inturned end 61 of said front section within the channel 60 and bringing the 30 lip 63 thereof into engagement with the pane of glass. When thus positioned, the rigid body members 66 of clip members 64 will be received within the cradle portion 54 and, upon tightening of the screws 69, the said body members will 35 be rocked in a clockwise direction within said cradle portion to flex the spring arms 65 and urge the lip 63 of the movable front section into yielding engagement with the pane of glass. When the depending lugs 70 engage the bottom 40 wall 53 of the rear section, further tightening of the adjusting screws 69 will be prevented so as to avoid the application of excessive clamping pressure upon the glass.

It is to be understood that the form of the invention herewith shown and described is to be taken as the preferred embodiment of the same, and that various changes in the shape, size and arrangement of parts may be resorted to without departing from the spirit of the invention or the 50 scope of the subjoined claims.

I claim:

1. In a sash or store front construction, the combination of a fixed section and a movable section adapted to receive and grip a pane of glass therebetween, said fixed section including a bottom wall substantially arcuately curved transversely to provide a longitudinally extending channel in its upper surface forming an arcuately grooved cradle portion, while said movable section comprises a face piece formed at its lower end with a longitudinally extending in-turned flange fitting beneath the forward upturned end of the bottom wall of the fixed section and having its inner edge arcuately curved to correspond to the curved underside of the bottom wall of said fixed section, a clip member carried by said movable section and having a rigid body member loosely seated within said cradle portion and provided with an arcuately curved bottom surface corresponding to and having sliding contact with the upper arcuately curved surface of the cradle portion, said movable section and clip member being removable laterally as a unit to lift the body member of the latter from said cradle portion, an adjusting member carried by said fixed section and engaging said body member for rocking the same within said cradle portion to urge said movable section into engagement with the glass, and an upstanding finger carried by said body member and engaging said spring arm for flexing the same upon rocking of said body member within said cradle portion.
2. In a sash or store front construction, the combination of a fixed section and a movable section adapted to receive and grip a pane of glass therebetween, said fixed section including a bottom wall substantially arcuately curved transversely to provide a longitudinally extending channel in its upper surface forming an arcuately grooved cradle portion, while said movable section comprises a face piece formed at its lower end with a longitudinally extending in-turned flange fitting beneath the forward upturned end of the bottom wall of the fixed section and having its inner edge arcuately curved to correspond to the curved underside of the bottom wall of said fixed section, a clip member comprising a substantially vertical spring arm carried at its upper end by said movable section and to the lower end of which is attached a rigid body member loosely seated within said cradle portion and provided with an arcuately curved bottom surface corresponding to and having sliding contact with the upper arcuately curved surface of the cradle portion, said movable section and clip member being removable laterally as a unit to lift the body member of the latter from said cradle portion, an adjusting member carried by said fixed section and engaging said body member for rocking the same within said cradle portion to urge said movable section into engagement with the glass, and an upstanding finger carried by said body member and engaging said spring arm for flexing the same upon rocking of said body member within said cradle portion.
3. In a sash or store front construction, the combination of a fixed section and a movable section adapted to receive and grip a pane of glass therebetween, said fixed section including a bottom wall substantially arcuately curved transversely to provide a longitudinally extending channel in its upper surface forming an arcuately grooved cradle portion having a radius not exceeding 180 degrees while said movable section comprises a face piece formed at its lower end with a longitudinally extending in-turned flange fitting beneath the forward upturned end of the bottom wall of the fixed section and having its inner edge arcuately curved to correspond to the curved underside of the bottom wall of said fixed section, a clip member comprising a substantially vertical spring arm carried at its upper end by said movable section and to the lower end of which is attached a rigid body member loosely seated within said cradle portion and provided with an arcuately curved bottom surface corresponding to and having sliding contact with the upper arcuately curved surface of the cradle portion, said movable section and clip member being removable laterally as a unit to lift the body member of the latter from said cradle portion, an adjusting member carried by said fixed section and engaging said body member for rocking the same within said cradle portion to urge said movable section into engagement with the glass, and an upstanding finger carried by said body member and engaging said spring arm for flexing the same upon rocking of said body member within said cradle portion.
4. In a sash or store front construction, the combination of a fixed section and a movable section adapted to receive and grip a pane of glass therebetween, said fixed section including a bottom wall substantially arcuately curved transversely to provide a longitudinally extending channel in its upper surface forming an arcuately grooved cradle portion, while said movable section comprises a face piece formed at its lower end with a longitudinally extending in-turned flange fitting beneath the forward upturned end of the bottom wall of the fixed section and having its inner edge arcuately curved to correspond to the curved underside of the bottom wall of said fixed section, a clip member comprising a substantially vertical spring arm carried at its upper end by said movable section and to the lower end of which is attached a rigid body member loosely seated within said cradle portion and provided with an arcuately curved bottom surface corresponding to and having sliding contact with the upper arcuately curved surface of the cradle portion, said movable section and clip member being removable laterally as a unit to lift the body member of the latter from said cradle portion, an adjusting member carried by said fixed section and engaging said body member for rocking the same within said cradle portion to urge said movable section into engagement with the glass, and an upstanding finger carried by said body member and engaging said spring arm for flexing the same upon rocking of said body member within said cradle portion.

tom wall substantially arcuately curved transversely to provide a longitudinally extending channel in its upper surface forming an arcuately grooved cradle portion having a radius not exceeding 180 degrees while said movable section comprises a face piece formed at its lower end with a longitudinally extending inturned flange fitting beneath the forward upturned end of the bottom wall of the fixed section and having its inner edge arcuately curved to correspond to the curved underside of the bottom wall of said fixed section, a clip member comprising a substantially vertical spring arm carried at its upper end by said movable section and to the lower end of which is attached a rigid body member loosely seated within said cradle portion and provided with an arcuately curved bottom surface corresponding to and having sliding contact

with the upper arcuately curved surface of the cradle portion, said movable section and clip member being removable laterally as a unit to lift the body member of the latter from said cradle portion, an adjusting member carried by said fixed section and engaging said body member for rocking the same within said cradle portion to urge said movable section into engagement with the glass, an upstanding finger carried by said body member and engaging said spring arm for flexing the same upon rocking of said body member within said cradle portion, and a positive stop means including coating parts on said clip member and fixed section for preventing further actuation of said adjusting member when said body member reaches a predetermined position in its rocking movement.

CLYDE D. LOWRY.
